INVENTOR,

Samuel M. Carter

UNITED STATES PATENT OFFICE.

SAMUEL McCARTER, OF NORRISTOWN, PENNSYLVANIA.

IMPROVEMENT IN CUT-OFF VALVES FOR STEAM-ENGINES.

Specification forming part of Letters Patent No. 118,340, dated August 22, 1871.

To all whom it may concern:

Be it known that I, SAMUEL McCARTER, of Norristown, in the county of Montgomery and State of Pennsylvania, have invented a certain Improvement in Cut-off Valves for Steam-Engines, of which the following is a specification:

My invention consists in a valve with a loose self-adjustable face, for the purpose of saving steam by cutting the steam off from the cylinder at half-stroke, more or less, as desired, and holding it in the cylinder on the piston to the end of the stroke without cramping the exhaust.

Figure 1 is a sectional side elevation, showing the openings in an ordinary steam-cylinder with steam-chest, valve-seat, valve, and rod, &c. Fig. 2 is a top view of the loose face P P, showing its construction.

The loose face P P and piece V are fitted and ground together, and provided with flanges l and l' at the ends, for the purpose of allowing the valve to lengthen and shorten itself at each end alternately while in operation, and also to give to the loose face P P its proper movement. The loose face P P is provided with two openings, B and B', for admitting the steam to the cylinder, and one opening, M, for exhausting it from the cylinder. This loose face P P is intended to move about one-half, ($\frac{1}{2}$), more or less, of the distance moved by the piece V, and is determined by the space between the flanges l and l'. This loose face P P is intended only to admit the steam to the cylinder through the openings B and B', and to exhaust it from the cylinder after it has done its work through the opening M into the exhaust-port E of the engine, while the piece V is intended to cut the steam off from passing into the cylinder only by moving over the openings B and B' alternately, thus making the leading-on and cutting-off points independent of each other.

This valve, V and P P combined, can be made to cut the steam off from the cylinder at any desired point of the stroke and equally at both ends,

and hold it in the cylinder on the piston to the end of the stroke and then exhaust freely, keeping open a wide communication with the exhaust-port E, thus allowing the piston to return without being retarded in the least, thereby getting the full benefit of the expansive force of the steam on the opposite side or end of the piston.

The piece V can be set to cut off, without regard to leading-on or exhausting, as the loose face P P performs both these operations itself when moved by the piece V coming in contact with the flanges l l', or their equivalent.

The position of the valve V P P, as shown in the drawing, is supposed to have been drawn by the valve-rod to the end of its movement, admitting the steam to the cylinder through opening B into steam-channel o. Now, the first movement from its present position would be for the valve-rod to force the piece V back, (the loose face P P standing still and holding open the exhaust with the steam-channel o'), pass over the opening B, and cut off the steam from passing into the cylinder through o, uncovering opening B', and then coming in contact with flange l, move the loose face P P until opening M leaves steam-channel o', closing it, and opening communication between exhaust-port E and steam-channel o, and admitting the steam to the other end of the cylinder by bringing opening B' over steam-channel o'. The effect of the return movement of the valve would, of course, be similar to that of the forward movement just described.

I claim—

The combined valve V P P with self-adjustable face, provided with flanges l l', or their equivalent, for the purpose of allowing the valve to shorten and lengthen itself at each end alternately while in operation, substantially and for the purpose hereinbefore set forth.

SAM'L. McCARTER.
